UNITED STATES PATENT OFFICE.

WHITNEY GOIT, OF KANSAS CITY, MISSOURI.

VENTILATING-SASH LOCK.

Application filed April 16, 1917; Serial No. 162,562. Renewed April 17, 1922. Serial No. 553,927.

To all whom it may concern:

Be it known that I, WHITNEY Goit, am a citizen of the United States, residing at Kansas City, in the county of Jackson and State 5 of Missouri, have invented certain new and useful Improvements in Ventilating-Sash Locks, of which the following is a specification.

This invention relates to ventilating window sash locks, and has for its object to produce a device which will permit the lower sash to be raised or the upper sash to be lowered a predetermined distance, but no further, regardless of the pressure applied 10 or how much the window is shaken, and which furthermore can not be unlocked by means of a wire or blade applied to the fastener through the crack or opening formed between the two sashes when one of 15 them is partly opened and the lock is in operative position. A further object is to produce a lock of the character mentioned which will not yield under the application of force applied through a crow bar or jimmy, unless 20 the force is sufficient to destroy the sashes or one of them.

Another object is to produce a simple, strong, durable, and cheap sash lock possessing the features of advantage above set 25 forth, and which can be easily and quickly applied in operative position by an unskilled person, and in which the retaining devices are not subjected to material strain in the event it is attempted to pry the lower sash 30 upward or the upper sash downward, but which, on the other hand, under such conditions, will utilize the lower sash to resist upward movement thereof or downward movement of the upper sash.

With the objects named in view, the invention consists in certain novel and peculiar features of construction and combinations of parts as hereinafter described and claimed; and in order that it may be fully 40 understood reference is to be had to the accompanying drawing, in which:

Figure 1, is a fragmentary inner side view of window sashes equipped with a ventilating window sash lock embodying my invention.

Figure 2, is a horizontal section on the line II-II of Figure 1, on an enlarged scale.

Figure 3, is a detail elevation of the sash lock as viewed in the direction indicated by 50 the arrow, Figure 2.

Figure 4, is a fragmentary elevation of the

sash lock viewed in the opposite direction to that indicated by said arrow.

Figure 5, is a section on the line V-V of Figure 4.

The sash lock comprises a stationary member 1 and a member 2 pivotally suspended and detachable from member 1.

The member 1 is in the form of a right angle shaped bar, comprising arms 3 and 4. 65 This bar is fitted at the desired height above the lower sash, to the inner corner of one of the vertical rails or sides of the upper sash, preferably the left hand rail or side as shown, the arms fitting flatly against said rail or side as shown clearly in Figure 2, and to retain the member 1 in the position referred to, screws 5 extend through the arm 3 and into the said rail or side of the upper sash. With the member thus arranged it will be seen that 70 there is a space produced between the molding edge of said rail or side and the arm 4 of the member, said space being identified by the reference character 6.

The arm 4 is provided with a plurality of 80 horizontally arranged key hole slots 7, the central portions of which are of greatest width. The function of these slots will hereinafter appear, it being understood however that the provision of a plurality of the slots 85 is to determine the amount of opening movement which can be imparted to either of the sashes or to both of the sashes, if it is desired to partly raise one and lower the other.

The adjustable pivoted member 2, 90 comprises a flat arm 8 to fit flatly against arm 4 of member 1, and a stop lug 9 to overlie the lower sash, said stop lug being disposed in a horizontal plane above the lower extremity of arm 8 so that when the lower sash is engaged with said stop lug it will be overlapped 95 at its outer side by the lower end of arm 8 which will be brought to bear against the upper rail of the lower sash, in the event an attempt is made to swing member 2 from the 100 full line position in Figure 3, toward the dotted line position, same figure, and in this connection it will be noted that to guard against lug 9 cutting the upper rail of the lower sash should the same be raised violently 105 or forced upward with considerable pressure, an arm 10 projects laterally from the lower end of the lug.

Stamped out of the arm 8 near its upper end, is a pair of tongues 11, said tongues 110 being bent to form oppositely projecting hooks, as shown most clearly in Figure 5.

These hooks are of size to readily pass through any of the openings 7, but are of such length conjointly, that when they extend cross-wise of the opening, they will 5 overlap the adjacent portions of arm 4 of member 1, and be incapable while in such position, of being withdrawn or disengaged from said last-named member. It is preferred that the slots 7 shall extend horizontally and that the hooks 11 shall extend vertically of their respective members, so 10 that it will be necessary to dispose member 8 in the position shown by dotted lines, Figure 3, in order to engage the two members 15 pivotally together as explained, it being understood in this connection that the inner arms of the hooks 11 extend through and operate pivotally in the widened central portion of the slot. In this connection it will 20 be noticed that the space 6 hereinbefore mentioned as being provided between the molding edge of the rail or sash and the arm 4 of member 1, accommodates the pivot hooks 11 of member 2 so that the latter shall 25 be free to operate pivotally as explained.

It is obvious that if a variation in adjustment is desired so as to give more ventilation, the member 2 will be engaged with the upper slot 7, and if the least ventilation is desired, the member 2 will be engaged with the slot 30 7 nearest the lower end of member 1. It is also obvious that the member 2 can be readily removed after being swung to substantially the position shown in dotted lines, Figure 3, 35 so as to leave the sashes free to be fully opened if desired.

By reference to Figure 3, it will be seen that any attempt to lower the outer sash or

raise the inner sash will result in the engagement of the stop lug 9 with the upper 40 edge of the inner sash. Under such engagement the member 2 tends to swing inwardly and upwardly, but this is prevented because that portion of said member which depends beyond the plane of the stop lug 45 will be caused to swing against the outer face of said sash and thus prevent appreciable pivotal movement.

From the above description it will be apparent that I have produced a sash lock embodying the features of advantage set forth as desirable in the statement of the object of the invention, and while I have illustrated the embodiment of the same which at this time appears the most practical, it is to be understood that I reserve the right to all changes which fall within the spirit and scope of the appended claim.

I claim:

A window sash lock, comprising a member of right angle shape in cross section and provided with a plurality of horizontally elongated openings at different points in the length of one of its arms, and a second member fitting flatly against the arm of the first-named member having the openings, and provided with a pair of bent tongues 60 detachably interlocked with the first-named member through one of its openings to permit a pivotal movement of the second member; said second member being widened at 65 an intermediate point in its length to provide a stop lug in a plane above the lower extremity of said member.

In testimony whereof, I affix my signature.
WHITNEY GOIT.
